MACHINE FOR INSERTING PILE WEATHER STRIPPING INTO GROOVES OF STORM WINDOW EXTRUSIONS

Max H. Ellenberg and Bernard Weiner, Philadelphia, Pa., and John I. Rouch, Nashville, Tenn., assignors to Storm Weather Products Co., Inc., Philadelphia, Pa.

Filed June 25, 1965, Ser. No. 467,073

9 Claims. (Cl. 29—235)

This invention relates to a machine for inserting tapes of pile weather stripping into the grooves of storm window extrusions. More particularly, it relates to a method and apparatus for incorporating flexible tapes within long lengths of metal extrusions that will ultimately be cut and fabricated into storm door and window components requiring a weather seal with a cooperating movable member.

As is well known, storm windows and doors are fabricated from 16 or 18-foot lengths of extruded aluminum members which are cut to size and subsequently mitered together as a frame about a suitably sized window. Usually, tapes of wool pile material are inserted within complementary slots or grooves in the extrusions, the pile being adapted to abut against a cooperating member so as to act as a seal in keeping out drafts. In the past, the wool pile tapes were threaded into the slots of the 16 or 18-foot extrusions by hand. This would require a workman starting at one end of the extremely long extrusion, threading one end of the tape from a spool into the groove, and then hand pulling the tape along the entire length of the extrusion. Such a manual operation necessarily resulted in a time-consuming and costly procedure. While machines for automatically inserting these tapes have been developed, it was difficult for the prior art machines to accommodate for changes in extrusion size, shape, and conformation as well as for variations in gauge of the tape being dispensed. All in all, what prior machines had been made were expensive in operation and costly to maintain.

It is therefore an object of this invention to provide a machine for automatically inserting flexible weather stripping tapes into grooves of storm window extrusions.

Another object of this invention is to provide a machine for easily inserting such tapes and at the same time accommodating rapidly and efficiently for any variations in tape gauge or in extrusion size, shape and conformation.

Still another object of this invention is to provide an apparatus and method for efficiently and economically incorporating flexible tapes of wool pile into the slots of storm window extrusions.

Yet another object of this invention is to provide a method for incorporating tapes of flexible material into slots of extrusions of any length.

Other objects of this invention are to provide an improved device of the character described which is easily and economically produced, that is sturdy in construction, and highly efficient and effective in operation.

With the above and related objects in view, this invention consists of the details of construction and combination of parts as will be more fully understood from the following detailed description when read in conjunction with the accompanying drawing in which:

FIGURE 1 is a top plan view of a machine for inserting pile weather stripping into grooves of storm window extrusions.

FIGURE 2 is an elevational view thereof taken generally along lines 2—2 of FIGURE 1.

FIGURE 3 is an enlarged fragmentary perspective view of the loading end of the machine.

2

FIGURE 4 is a fragmentary top plan view of the releasing or terminal end of the machine.

FIGURE 5 is a perspective view showing the manner in which the weather stripping is started into the extrusion groove.

FIGURE 6 is a sectional view taken along lines 6—6 of FIGURE 5.

Referring now in greater detail to the drawings in which similar reference characters refer to similar parts, the tape 10 inserting machine of the instant invention comprises a frame, generally designated as A, a carrier member B longitudinally movable in said frame, and jaw means C secured to the carrier member and adapted to grasp tape D dispensed from a reel at one end of the machine and thread the same through an elongated extrusion E to the other end.

The frame A of the machine comprises a horizontal table member 10 supported by suitable legs 12 which can be made of angle iron, for example. Mounted at opposite ends of the frame A are bearings 14 and 16 for journaling the shafts of respective pulleys 18 and 20 about which a continuous carrier belt 22 is trained. The table top is approximately 18 feet long so as to accommodate the nominal standard 16-foot lengths of extrusion stock E. An adjustable stop member 24 is bolted to the table top 10 at the discharge end of the machine and is adapted to orient and rapidly position each extrusion E with respect to the jaw means C in preparation for threading of the tape D therethrough.

30 The carrier member B which includes the belt 22 entrained about the pulleys 18 and 20, is driven by a conventional motor-gear reducer unit 26 so that the belt 22 will travel at a longitudinal speed of approximately 2½ feet per second. A limit switch 28 is mounted at the loading end of the machine and has series contacts for connecting the motor 26 to a suitable source of electric power. The switch 28 may be a rotary, oil-tight limit switch, such as is described in Allen-Bradley Bulletin No. 802T and having a pivot arm 30. Moving rotary arm 30 by hand to the downwardly depending position shown by the dotted lines in FIGURE 3, will couple the motor 26 to the source of electrical power and cause said motor to run the carrier member B. The carrier member B will continue to run in a clockwise direction, as shown in FIGURE 3, until one of the jaw members C engages the switch arm 30, and cause it to turn upwardly through 90° so as to open the internal switch contacts and stop the motor. At the other end of the machine and vertically upstanding from the table top 10 is a stationary vertical rod or post 32 which also is in the path of and engages the jaw means C as each passes thereby to release the tape D automatically at the end of each extrusion threading operation. See FIGURE 4.

55 The jaw means C and C1 comprise a pair of holding members which are secured to the belt 22 and are peripherally spaced from each other by 180°. Jaw C is adapted to grasp the end of the tape D after the latter has been partially threaded or engaged within the longitudinally extended slot or groove provided therefor in the extrusion E. After the jaw C has pulled the tape D through an extrusion E as a result of rotation of the carrier B and has automatically released the tape at the end of its stroke, the jaw C1, 180° in advance, will have engaged the arm 30 of switch 28 to cut off the power to the motor 26. The jaw C1 will then coast around to the loading position previously occupied by the jaw C.

60 The jaws C and C1 are identical in every respect, each comprising a stationary portion 34 having a bracket or flange 36 secured to the belt 22 by bolts 38. A movable jaw 40 is hingedly secured to the stationary jaw 34 and pivotally supported about trunnion 42. The lower portion of the movable jaw 40 has a pad or cushion 41

which is adapted to abut the fixed jaw 34. A stud 44 is threaded into the fixed jaw 34 and freely extends through an opening 45 in the movable jaw 40 and its pad 41. Coil spring 46 is concentrically interposed about stud 44 in compression between the stud head and the back of the movable jaw 40 so as to normally bias the latter into abutment with the fixed jaw 34. Projection 39 at the inboard end of the movable jaw extends above the belt 22 and is adapted to open the movable jaw 40 against the bias of the spring 46 either by hand during loading of the tape D or by abutment with the post 32 during its pass so as to automatically release the tape. The projecting arm 39 also serves to actuate the arm 30 so as to open the contacts of switch 28.

The tape D comprises long thin strips of backing 50, approximately $\frac{1}{32}$ inch thick by $\frac{1}{4}$ inch wide, from which a somewhat narrow band of pile 52 extends outwardly. The strip 50 is inserted within a longitudinally extending slot or channel 54 in the extrusion E so that the pile portion 54 projects above the surface whereby the weather stripping C can perform its assigned task. The extrusions E are 16 or 18 feet long, and after the tapes D are inserted, they are cut and mitered to the appropriate size to frame the window itself.

The tape D is dispensed as a continuous roll from a reel 48 at the loading end of the machine. See FIGURE 2. One end of the tape D is slightly twisted and sited as shown in FIGURE 5 into the slot 54 at the proximal end of the extrusion E placed on the table top 10. The jaw C overlying the loading end is manually opened by pressing against projection 39. The end of the tape D is grasped when the bias of the spring 46 closes the movable jaw member 40. The arm 30 is now swung downwardly by hand to close the switch 28 and actuate the motor power circuit. See FIGURE 3. The carrier B will turn in a clockwise rotation, as shown in FIGURE 1, and the jaw C will travel longitudinally with the belt 22. When the jaw C passes the post 32, projection 39 is engaged thereby to release the tape D after it has been entirely threaded through the extrusion slot 54. Meanwhile, the jaw C1 will have moved around pulley 18 where its projection 39 will kick against the limit switch arm 30 to open the motor 26 contacts. The carrier B will coast around slightly until the jaw C1 is in loading position. The tape D is cut or broken at the proximal end overlying the loading portion of the table 10 so that the tape threaded extrusion E now completed can be removed and a new extrusion loaded.

Although our invention has been described in considerable detail, such description is intended to be illustrative rather than limiting since the invention may be variously embodied and the scope of the invention is to be determined as claimed.

What is claimed is:

1. A machine for inserting tapes of pile weather stripping into grooves of elongate extrusions comprising: a frame, a table portion for supporting extrusion to be weather stripped on said frame, a pair of pulleys rotatably supported in said frame and horizontally spaced from each other a distance substantially equal to the length of one extrusion, a continuous belt carried by said pulleys at a height just above said table portion, a pair of jaws secured to said belt at 180° peripheral intervals from each other, motor drive means coupled to one of said pulleys, an electrical switch on said frame adjacent the loading end thereof and electrically coupled with said motor, a pivotal arm on said switch for hand movement into a position at which said motor will be actuated to drive said belt in a preferential direction, said pivotal arm when in motor actuating position being interposed in the path of travel of said jaws so as to be engaged upon and shut said motor off automatically as each jaw passes thereby, one of said jaws grasping an end of the tape being threaded into the extrusion at the loading end of the table, and means at the terminal end of said table

engaging said tape loaded jaw and automatically releasing the tape therefrom in its passage thereby so that one of said jaws will longitudinally insert the tape along the entire length of the extrusion groove while the other of said jaws will turn the machine off after the extrusion is weather stripped.

2. A machine for inserting tapes of pile weather stripping into grooves of elongate extrusions comprising a table supporting one of said extrusions at a time and having a loading end and a terminal end, a continuous carrier rotatably supported as a closed loop in said table, a pair of jaws secured to said carrier and spaced from each other at 180° of arc, one of said jaws being initially positioned at a loading end of said table and adapted to grasp an end of tape being threaded into the extrusion, means to turn said carrier, discharging means at the terminal end of said table interposed in the path of travel of the jaw grasping the tape and automatically actuating the release thereof in passage thereby, and switch means at the loading end of said table interposed in the path of travel of the other of said jaws and actuated thereby to cut off said means to turn and stop said carrier automatically after the first jaw has completed a longitudinal stroke.

3. The invention of claim 2 wherein resilient means biases each of said jaws into closed position, and a projection on said jaws engages against said discharging means in respective passage thereby to open said jaws against the bias of said resilient means.

4. A machine for inserting tape into an extrusion member comprising:
means for supporting the extrusion member and having a loading end and a terminal end,
jaws normally biased into closed position for grasping the tape,
means for conveying said jaws along a path substantially parallel to the supported extrusion member, and tripper means adjacent the terminal end of the said extrusion supporting means and interposed in the path of travel of said jaws for automatically actuating the opening thereof as said jaws pass thereby, whereby tape grasped by said jaws at the loading end and started into said extrusion member will be threaded therethrough to the terminal end at which time said tripper means will automatically cause said jaws to open against the opposing bias holding them closed and release the tape therefrom.

5. The machine of claim 4 including means for actuating the movement of said conveying means at the starting portion of the cycle, and means for automatically stopping the movement of said conveying means at the end portion of the cycle.

6. The machine of claim 5 wherein one of said jaws is movable and the other of said jaws is affixed to said conveying means, said movable jaw including a projection for engaging said tripper means.

7. The machine of claim 6 wherein said tripper means constitutes a stationary member affixed to said extrusion supporting means.

8. The machine of claim 5 wherein said means for automatically stopping the movement of said conveying means constitutes a switch including a lever interposed in the path of travel of said jaws.

9. A machine for inserting tape into an extrusion comprising:
means supporting said extrusion and having a loading end and a terminal end,
means constituting a carrier for moving in a direction substantially parallel to said extrusion and spaced adjacent thereto,
a fixed jaw member supported on said carrier,
a movable jaw member coupled with said fixed jaw member,
means biasing said movable jaw member toward said

fixed jaw member so that the tape can be grasped therebetween at the loading end of said extrusion supporting means,
and tripper means adjacent the terminal end interposed in the path of travel of said movable jaw member and engaging therewith as said movable jaw passes thereby so as to actuate the release of the tape automatically at the terminal end.
